UNITED STATES PATENT OFFICE

CORA L. HILL, OF LOS ANGELES, CALIFORNIA

LINGERIE HOLDER

Application filed March 2, 1931. Serial No. 519,359.

This invention relates to ladies' wearing apparel and more especially to lingerie holders.

It is an object of the present invention to 5 provide a simple, all-metal lingerie holder of durable construction and yet of low cost.

A further object is to provide a holder of this class which is wholly devoid of fabric or cloth elements which are known to become 10 quickly soiled when in use.

A further object is to provide a lingerie holder incorporating means to provide for its ready attachment and detachment at will and therefore to eliminate stitching in or 15 making other permanent connections as by stapling of fastening means.

A further object is to provide a lingerie strap holder incorporating a combination of all-metal members including chain parts and 20 a small snap fastener, including a metallic socket element and a complementary pin element associated with a small and substantial safety pin all of which parts are well known and of popular character and are devoid of 25 strange features of unusual mode of application or operation which is objectionable in the pioneer introduction of a new article of manufacture.

The invention consists in certain advancements in this art as set forth in the ensuing disclosure and having, with the above, additional objects and advantages, and whose construction, combination and details of means, and the manner of operation will be 35 made manifest in the description of the here-with illustrative embodiment; it being understood that modifications, variations and adaptations may be resorted to within the scope, principle and spirit of the invention as 40 it is more directly claimed hereinafter.

Figure 1 is a perspective showing the device as in use.

Figure 2 is a plan of a preferred form of the holder.

Figure 3 is a plan of a slightly modified form.

Figure 4 is a plan of a further variant.

The holder comprises a safety pin 2 of a conventional structure, incorporating end openings 3 and 4, in which hang loops, 5 and

6, at the ends of a bight of chain 7 which is rove through holes 8 and 9 in one element 10 of a glove snap fastener. Attached to the fastener element 10, is one end of a chain 11 to whose other end is attached the complementary fastener element 12; one of which elements constitutes the socket part while the other is the pin or button part; such fasteners being in extensive general use and well known to the feminine public. 55 60

A slightly modified form of the fastener is shown in Fig. 3, in which the bight of chain 7 is attached to its element 10 by a hitch ring 13 passed through a hole in the element 10. 65

In application of the holder the pin 2 is applied in the usual manner to the shoulder hem of the dress and then the chain 11 is passed around the shoulder strap S and the fastener element 12 is brought up to and snapped onto the element 10. 70

In Figure 4 the pin back bar has a center loop 2^a to which the chain 7^a is connected; thus using a shorter piece of chain than the bights 7, of Figures 2 and 3. 75

What is claimed is:

1. A lingerie holder comprising, in combination, a safety pin of a structure presenting end holes, a bight of chain whose ends are hitched to the pin at the end holes, a snap fastener element attached to the loop of the bight and having a stretch of free chain provided at its end with a fastener element which is complementary to the aforesaid bight-carried element. 80

2. A lingerie holder comprising, in combination, a safety pin of a structure presenting end holes, a bight of chain whose ends are hitched to the pin at the end holes, a snap fastener element attached to the loop of the bight and having a stretch of free chain provided at its end with a fastener element which is complementary to the aforesaid bight-carried element; said bight loop being passed through respective apertures in the contiguous snap element. 85 90 95

3. A lingerie holder having a safety pin, a chain attached to the safety pin and to a contiguous snap fastener element, a stretch of chain pendant from the said element and having at its end a snap fastener element 100

complementary to the first mentioned element.

4. A lingerie holder having a safety pin, a chain attached to the safety pin and to 5 a contiguous snap fastener element, a stretch of chain pendant from the said element and having at its end a snap fastener element 10 complementary to the first mentioned element; the back bar of the pin having a loop to which the chain end is attached.
